DRINK MIXING AND DISPENSING DEVICE

Oscar L. Engstrom, Long Island City, N. Y.

Application March 6, 1956, Serial No. 569,935

8 Claims. (Cl. 222—133)

My invention relates to drink dispensing devices and is directed particularly to a device for mixing syrup and water for soda fountain drinks.

Drink dispensing devices incorporating syrup chambers and valves for dispensing a metered amount of syrup mixed with plain or carbonated water are known. These known devices are generally deficient, however, in that they do not consistently supply the same amount of syrup, with the result that the strength of the dispensed drinks varies from glass to glass.

It is accordingly the principal object of my invention to provide a drink mixing and dispensing device that will consistently deliver drinks having equal proportions of syrup and water for a given dispensed amount of drink.

Another more specific object of my invention is to provide a drink mixing device of the character described having a syrup chamber, a mixing chamber below the syrup chamber, and means effective upon actuation of the device to flush the residual syrup from the syrup chamber while the drink is being dispensed.

Still another object of my invention is to provide a mixing device of the character described which is comparatively simple in construction, efficient in operation, and easy to use, clean and repair.

Further objects and advantages of my invention will become apparent as the following description proceeds; and the features of novelty which characterize my invention will be pointed out with particularity in the claims annexed to and forming a part of this specification.

In the drawings, wherein like reference numerals denote corresponding parts throughout the several views:

Fig. 1 is a top view of the drink mixing and dispensing device embodying the invention;

Fig. 2 is a vertical sectional view taken along the line 2—2 of Fig. 1 showing the device in actuated condition wherein the discharge valve and the water inlet valves are closed and the syrup inlet valve is open;

Fig. 3 is a vertical sectional view taken along the broken line 3—3 of Fig. 1, in the direction of the arrows, through the syrup opening of the syrup chamber;

Fig. 4 is a horizontal cross-sectional view taken along the line 4—4 of Fig. 2 looking downwardly;

Fig. 5 is a horizontal sectional view taken along the line 5—5 of Fig. 2 looking downwardly;

Fig. 6 is a horizontal cross-sectional view taken along the line 6—6 of Fig. 2 looking downwardly;

Fig. 7 is a horizontal cross-sectional view taken along the line 7—7 of Fig. 2 looking downwardly;

Fig. 8 is a horizontal cross-sectional view taken along the broken line 8—8 of Fig. 2 looking downwardly;

Fig. 9 is a vertical sectional view equivalent to Fig. 2 but on a larger scale;

Fig. 10 is a view similar to Fig. 9 but showing the operating handle in partly actuated position for dispensing a drink, and

Fig. 11 is a view similar to Fig. 9 but showing the operating handle in fully actuated position.

Referring now in detail to the drawings, the drink dis-

2

pensing device is comprised of an upper cylindrical housing member 10, a lower cylindrical housing member 12 removably attached to said upper housing member 10 by a screw flange 14, and a handle 16 extending upwardly from said lower housing member and operative when pulled downwardly to dispense a mixed drink through an opening 18 in the lower end of the lower housing member 12. The lower portion of the upper cylindrical housing member 10 is cylindrically recessed to provide a syrup chamber 20. A cylindrical valve structure 22 is coaxially disposed within the upper cylindrical housing member 10 and is fixed therein by having a reduced diameter upper portion of said valve structure press-fitted in a central opening in the upper portion of said upper housing member.

The upper end of the valve structure 22 is drilled to provide a water inlet chamber 24. The upper portion of the upper cylindrical housing member 10 is drilled and tapped as indicated at 26 to receive a water inlet conduit 28 (partially shown). The inner end of the water inlet opening is drilled through to the water inlet chamber 24 as indicated at 30. The bottom of the water inlet chamber 24 is bored as indicated at 32 so as to provide an annular valve seat 34. The water inlet chamber 24 is fitted with a coaxial water valve member 36 having an intermediate annular flange portion, an upwardly extending spring locating portion 38, and an actuating rod portion 40 extending downwardly through the bore 32. A valve washer 42, preferably of rubber or neoprene, is securely seated against the underside of the annular flange portion of the water valve member. A water valve spring 44 is circumferentially located with respect to the upwardly extending spring locating portion 38 and has its lower end seated against the upper annular surface of the intermediate annular flange portion thereof. The upper end of the water valve spring 44 is held under compression by means of a screw cap 46 threaded into the upper end of the valve structure 22. A washer 48 is provided under the screw cap 46 to seal off the water inlet chamber 24.

The valve structure 22 has a cylindrical wall portion 50 extending downwardly into the syrup chamber 20. The upper portion of the cylindrical wall 50 is cross drilled to provide a pair of aligned openings 52. Valve means are provided comprising an inner valve sleeve member 60 and an outer valve sleeve member 54, said cylindrical outer valve sleeve member 54 being slidably mounted on the cylindrical wall 50 of the valve structure 22. The outer valve sleeve member 54 has a cylindrical lower end portion 56 slidably disposed within the lower cylindrical housing member 12. The cylindrical lower end 56 of the outer valve sleeve member 54 is hollow to provide a mixing chamber 58. The coaxial inner valve sleeve member 60 has a valve sleeve portion 62 slidably fitted within the cylindrical wall 50 of the valve structure 22, an intermediate cylindrical portion 64 of somewhat reduced diameter 55 extending below said valve sleeve portion, and a lower end cylindrical portion of still further reduced diameter 66. The lower end cylindrical portion 66 of the inner valve sleeve member 60 is cross drilled and fitted with a cross pin 68 having its opposite ends fitted within opposed openings in the cylindrical lower end 56 of the outer valve sleeve member 54. (See Fig. 8). The outer valve sleeve member 54 and the inner valve sleeve member 60 are thereby joined together for simultaneous up and down sliding motion with respect to the rest of the valve structure.

The lower end 66 of the valve sleeve member 60 terminates in a threaded stud 70. A wire mesh strainer 72 is seated on the threaded stud 70 and secured in place by a plug supporting piece 74. The external diameter of the strainer 72 is approximately the same as the internal diameter of the mixing chamber 58 to insure additional

mixing and also provide straining of the beverage as it passes down through the mixing device. A plug valve member 76 is secured to the lower end of the plug supporting piece 74. The lower end of the plug valve 76 is rounded to provide good sealing action when seated down against the conical valve seat 78 formed at the lower end of the lower cylindrical housing member 10 about the discharge opening 18 thereof.

The valve sleeve portion 62 of the inner valve sleeve member 60 is formed with an internal upstanding post 80 having a recess 82 in the upper end thereof. The upstanding post 80 defines an annular recess within the valve sleeve portion 62. The lower end of the actuating rod portion 40 of the water valve member 36 extends partially within the recess 82 of the upstanding post 80 when the mixing device is in unactuated condition as illustrated in Fig. 9. A coaxial compression spring 84 has its lower end seated against the annular floor surrounding the upstanding post 80 and within the inner valve sleeve member 60, and its upper end constrained against the annular surface surrounding the bore 32 opposite the annular valve seat 34 in the valve structure 22. The compression spring 84 serves to urge the inner valve sleeve member 60 downwardly so that the plug valve 76 is normally seated in sealing engagement against the conical valve seat 78, as illustrated in Fig. 9.

The valve sleeve portion 62 of the inner valve sleeve member 60 is provided with opposed openings 86. The outer sleeve member 54 is formed with a cylindrical upper end portion 88 of reduced diameter providing an annular shoulder 90. Slidably disposed on the cylindrical upper end portion 88 is an annular syrup and vent shut-off member 92. Circumjacent the cylindrical upper end 88 is a spring 94 constrained between the lower annular surface of the annular syrup and vent shut-off member 92 and the annular shoulder 90 of the outer valve sleeve member 54. A retaining split ring 96 is seated in a groove around the cylindrical upper end portion of the outer sleeve member 54.

The upper end of the upper cylindrical housing member 10 is provided with a pair of vertically drilled syrup and air vent openings 98 and 100, respectively, communicating with which are syrup and air vent conduits 102 and 104.

The upper end portion 88 of the outer sleeve member 54 is provided with a pair of cross drilled openings 106 in alignment with the openings 86 in the valve sleeve portion 62 of the inner valve sleeve member 60. The intermediate cylindrical portion 64 of the inner valve sleeve member 60 is also cross drilled to provide a pair of smaller openings 107. These openings allow the mixing water to flow from within the valve structure 22 down into the mixing chamber 58 when the valve is being operated, as is hereinbelow more particularly described.

The cylindrical lower end 56 of the outer valve sleeve member 54 is provided with a pair of large cross drilled openings 109 communicating with the upper end of the mixing chamber 58. The vertical position of the openings 109 is such that when the mixing device is in fully actuated condition as illustrated in Fig. 11, said openings will be in full communication with the lower surface of the syrup chamber 20. Preferably the floor of the syrup chamber 20 is inclined as indicated at 111 so that the syrup will readily drain out through the openings 109 and into the mixing chamber 58 when the mixing device is operated.

The operating handle 16 is fixed at its lower end as by set screw 108 (Fig. 3) to a pinion shaft 110 (Fig. 8). The side of the lower cylindrical housing member 12 is formed with a concave portion 112 having a threaded opening to receive a headed bushing 114. The bushing 114 journals the pinion shaft 110 in the housing 112. A packing washer 118 is provided under the head of the bushing 114. A packing washer 116 is also disposed at the inner end of the pinion shaft 110. The inner end of the pinion rod 110 is integrally formed with a pinion 120.

cooperatively engaged with rack teeth 122 cut along the side of the cylindrical lower end portion of the outer valve sleeve member 54.

Referring now to Fig. 9 of the drawings and considering the operation of the drink dispensing device, it will be seen that when in the unactuated condition the syrup and vent shut-off member 92 will be removed from the upper surface of the syrup chamber 20, thereby allowing a full charge of syrup to flow into said chamber through syrup conduit 192. It will also be noted that when in unactuated condition, the plug valve 76 is firmly seated down against the conical valve seat 78 by action of the compression spring 84, thereby preventing dripping and also eliminating the possibility of insects entering the mixing chamber. Water pressure from the inlet conduit 28 acts downwardly upon the valve member 36 in addition to the force exerted by water valve spring 44 to insure effective water shut-off at the valve seat 34.

When the operating handle 16 is being operated for dispensing a mixed drink, upward movement of the outer valve sleeve member 54 (Fig. 10) will first raise the shut-off member 92 to block the syrup and vent openings 98 and 100. Further downward movement of the operating handle 16 raises the inner valve sleeve member 60 so that it begins to act upon the rod portion 40 to open the water valve. Water will then begin to flow through the interior of the valve sleeve portion 62 and out the small openings 107 therein. Further downward movement of the operating handle allows water to flow through the device with greater volume and at the same time further raises the outer valve sleeve member 54 so that its large syrup discharge openings 109 are in communication with the syrup chamber 20. Syrup and water will now be flowing together and mixing in the mixing chamber 58, the mixing action being enhanced by the screen 72. Completed downward movement of the operating handle 16 (Fig. 11) moves the syrup discharge openings 109 into full communication with the syrup chamber 20 and at the same time moves the openings 86 and 106 in the respective inner and outer valve sleeve members 60 and 54 into alignment with the openings 52 of the valve structure 22. Water will thus finally flow under pressure into the syrup chamber 20 to flush out all remaining syrup. By virtue of the inclined lower annular surface 111 of the syrup chamber 20, water and syrup will be completely drained, insuring that each succeeding syrup charge will be the same as the last, and thereby insuring that all drinks will be of the same strength. By proper dimensioning of the sizes of the various fluid flow openings, action can be had such that the drink is substantially fully mixed at uniform drink strength as it issues from the dispenser.

While there is shown and described a particular embodiment of the invention, it will occur to those skilled in the art that various changes and modifications may be made without departing from the invention. I therefore aim in the appended claims to cover all such changes and modifications as fall within the true spirit and scope of my invention.

What is claimed is:

1. In a mixing dispenser for carbonated water-syrup drinks, the combination comprising a housing structure containing an annular syrup chamber in the upper end thereof and a mixing chamber in the lower end thereof, normally open syrup inlet means communicating with said syrup chamber, a valve structure having a cylindrical wall centrally disposed in said housing structure, normally closed water inlet means in the upper end of said housing structure and communicating with the interior of said valve structure, valve means comprising a cylindrical inner valve sleeve member and a concentric cylindrical outer valve sleeve member slidably mounted in concentric relation with respect to said valve structure, manual control means for moving said valve means from an unactuated position to an actuated position, means con-

trolled by actuation of said valve means to open said water inlet means, close said syrup inlet means and to provide communication channels from the lower end of said syrup chamber to said mixing chamber and from the interior of said valve structure to said syrup chamber, said channel communicating from the interior of said valve structure to said syrup chamber comprising openings in said inner and outer sleeve members and in said valve structure operative to move into registry with one another, whereby said syrup chamber will be completely flushed out upon the dispensing of a mixed drink.

2. In a mixing dispenser for carbonated water-syrup drinks, the combination comprising a housing structure containing an annular syrup chamber in the upper end thereof and a mixing chamber in the lower end thereof, normally open syrup inlet means communicating with said syrup chamber, a valve structure having a cylindrical wall centrally disposed in said housing structure, normally closed water inlet means in the upper end of said housing structure and communicating with the interior of said valve structure, valve means comprising a cylindrical inner valve sleeve member and a concentric cylindrical outer valve sleeve member slidably mounted in concentric relation with respect to said valve structure, manual control means for moving said valve means from an unactuated position to an actuated position, means controlled by actuation of said valve means to successively open said water inlet means, close said syrup inlet means, provide a channel communicating between the lower end of said syrup chamber and said mixing chamber, and provide a channel communicating between the interior of said valve structure and said syrup chamber, said channel communicating from the interior of said valve structure to said syrup chamber comprising openings in said inner and outer sleeve members and in said valve structure operative to move into registry with one another, whereby the syrup chamber will be completely flushed out upon the dispensing of a mixed drink.

3. In a mixing dispenser for carbonated water-syrup drinks, the combination comprising a housing structure containing an annular syrup chamber in the upper end thereof and a mixing chamber in the lower end thereof, normally open syrup inlet means communicating with said syrup chamber, a valve structure having a cylindrical wall centrally disposed in said housing structure, normally closed water inlet means in the upper end of said housing structure and communicating with the interior of said valve structure, valve means comprising a cylindrical inner valve sleeve member and a concentric cylindrical outer valve sleeve member slidably mounted in concentric relation with respect to said valve structure, manual control

means for moving said valve means from an unactuated position to an actuated position, a drink flow opening at the lowermost end of said mixing chamber, a plug member fixed with respect to said valve means and normally seated in sealing engagement against said drink flow opening, and means controlled by actuation of said valve means to successively open said water inlet means, close said syrup inlet means, provide a channel communicating between the lower end of said syrup chamber and said mixing chamber, and provide a channel communicating between the interior of said valve structure and said syrup chamber, said channel communicating from the interior of said valve structure to said syrup chamber comprising openings in said inner and outer sleeve members and in said valve structure operative to move into registry with one another, whereby the syrup chamber will be completely flushed out upon the dispensing of a mixed drink.

4. The device as defined in claim 3 including a resilient means normally constraining said valve means in unactuated condition.

5. The device as described in claim 4 wherein said mixing chamber is cylindrical, and wherein said means providing a channel communicating between the lower end of said syrup chamber and said mixing chamber comprises side openings in said outer valve sleeve member communicating with said mixing chamber.

6. The device as described in claim 4 wherein said water inlet opening means comprises a central bore in said upper end of said valve structure, a valve member having a flange portion seatable on said bore and having a rod portion extending through said bore, and a spring normally constraining said flange portion in unactuated, seated condition.

7. The device as described in claim 4 wherein said syrup inlet closure means comprises an annular shut-off member within said syrup chamber and surrounding said outer valve sleeve member resiliently supported thereon for relative axial movement, said shut-off member being adapted to abut against said syrup inlet means during actuation of said valve means.

8. The device as defined in claim 4 wherein said means providing a channel between the interior of said valve structure and said syrup chamber comprises an aligned pair of openings in each of said inner valve sleeve member, said outer valve sleeve member and said valve structure.
